COMMUNICATION KEYBOARD

Allen G. Jacobson, Ramsey, N.J., assignor to Computer
Transceiver Systems, Inc., Paramus, N.J.

Continuation-in-part of design application Ser. No. 16,968,

Apr. 30, 1969, which is a continuation-in-part of design
application Ser. No. 12,846, July 22, 1968. This appli-
cation Apr. 23, 1970, Ser. No. 22,586

Term of patent 14 years

Int. Cl. D14—02

U.S. Cl. D26—5

FIG. 2

FIG. 1

FIG. 3

FIG. 4

FIG. 1 is a perspective view of a communication keyboard embodying my new design;

FIG. 2 is a front elevation thereof;

FIG. 3 is a top plane view thereof;

FIG. 4 is an end elevation thereof.

This application is a continuation-in-part of my application Ser. No. D. 16,968, filed Apr. 30, 1969, which in turn is a continuation-in-part of my application Ser. No. D. 12,846, filed July 22, 1968.

I claim:

The ornamental design for a communication keyboard, as shown.
